CALCULATOR

Sol Weiss, Philadelphia, Pa.

Application November 28, 1950, Serial No. 197,973

5 Claims. (Cl. 235—78)

My invention relates to calculators, and relates particularly to a pocket calculator of the circular variety.

It is an object of my invention to provide a small pocket calculator by means of which columns of figures may be quickly added and totaled, and also, by means of which subtraction may be made, simply by reversing the minuend operation of the machine.

Another object of my invention is to provide a calculator of the character described which is positive in operation and incapable of error when correctly manipulated.

Another object of my invention is to provide a small pocket calculator which has relatively simple parts which do not wear or easily get out of order.

Another object of my invention is to provide a pocket calculator which is easily read and easily actuated.

Another object of my invention is to manufacture a small calculator wherein the parts may be easily molded of a plastic or synthetic resin.

Other objects of my invention are to provide an improved device of the character described, that is easily and economically produced, which is sturdy in construction, and which is highly efficient in operation.

With the above and related objects in view, my invention consists in the details of construction and combination of parts, as will be more fully understood from the following description, when read in conjunction with the accompanying drawing in which:

Fig. 1 is a top view of the calculator, portions of which are cut away to reveal the construction.

Fig. 2 is a fragmentary perspective view of the calculator seen from above with one counter ring exposed.

Fig. 3 is a detailed fragmentary view showing the digit transfer mechanism in inoperative position.

Fig. 4 is a detailed fragmentary view showing the digit transfer mechanism in operative position.

Fig. 5 is a sectional view taken along the line 5—5 of Fig. 1.

Fig. 6 is a perspective view of the ring, the catch, and the catch holding spring.

Fig. 7 is a fragmentary perspective view of the bottom piece of the calculator.

Fig. 8 is a bottom view of the top piece of the calculator.

Fig. 9 is a sectional view taken along the line 9—9 of Fig. 8.

Fig. 10 is a sectional view taken along the line 10—10 of Fig. 8.

Fig. 11 is a perspective view of the slide itself.

Fig. 12 is a perspective view of the stylus.

Referring now to the drawings, wherein similar reference characters refer to similar parts, I show a circular calculator with a top portion, generally designated as A1, of a case, a complementary bottom case portion, generally designated as B, forming a case wherein there are a plurality of counter rings, each of which is generally designated with the prefix C. Each ring C has ten equally spaced notches N in its outer curved surface to permit the insertion of a stylus, pencil point, or other sharp pointer for turning the ring and a communicating notch N1 is adapted to be engaged by a catch, generally designated as E. The upper face of each ring C carries the digits 0, 1, 2, 3, 4, 5, 6, 7, 8 and 9 at equal intervals in black color as viewed clockwise, and beside each of the aforementioned digits is the digit 9, 8, 7, 6, 5, 4, 3, 2, 1, 0 in red color, the digits being located between the successive notches N which are spaced

2

36 degrees apart. The digits on the face of the rings are not visible when inserted within the case, except through the totalizing windows A2. The bottom of each ring C carries a short projection 11, see Fig. 6, which is located beneath the 3-4 digits for addition and the 4-5 digits for subtraction. The function of the short projection 11 will hereinafter be further described. The outermost ring, designated as C1 indicates units, the next ring C2 indicates tens, ring C3 indicates hundreds, ring C4 indicates thousands, and the innermost ring C5 indicates tens of thousands. In the drawing, I have shown a calculator having five rings which can handle totals up to five figures, but the calculator may have any desired number of rings.

15 The upper outer surface A3 of the top case portion A1 is provided with a plurality of concentric annular slots designated as A4, A5, A6, A7 and A8 which overlie rings C1, C2, C3, C4 and C5, respectively. These annular slots extend a distance of $\frac{1}{10}$ of the circumference of each of the rings, however, each of the slots A4 to A8, respectively, expose the notches N in the particular counter ring C which it overlies. The remaining $\frac{1}{10}$ of the upper surface is closed except for a plurality of windows or apertures therein which are covered by a 20 slide, generally designated as D, see Fig. 11. The aperture A2 is where the numerals on each ring appear and may be designated the totalizing aperture.

The windows in the top case portion A1 enable pre-determined portions of the slide D, to be visible there-

25 through. The slide D is an elongated thin member 10 having a plurality of openings D1 therein so that only one digit on one ring may be seen at one moment of time. A tab 12 carries the notation S—A (S to indicate for subtraction and A for addition), a second tab 14 integrally formed with the body member 10 has a vertical handle 16 which serves as a pusher so that S or A may be pushed to be visible. The ends 20, 22 are slightly upturned to permit easy sliding of the slide D.

The uppermost surface of each ring C carries the digits 30 0 through 9 equally spaced and arranged in ascending order in a counter-clockwise direction (red color) and also in a clockwise direction (black color) so that the surface has numerals which read 9—0, 8—1, 7—2, 6—3, 5—4, etc. The red numerals arranged in a counterclockwise direction are used for performing subtraction, as will hereinafter be described.

35 The under portion of the case has a plurality of circular walls 25, 26, 27, 28, 29, 30, 31. The walls 25 to 29 extend adjacent the annular slots A4 to A8, respectively. The vertical walls 26 to 30 cover the same circular distance that the slots A4 to A8 extend.

40 Those portions of the vertical walls 26 to 30 which are included in the central angle defined by the numerals 9 and 0 on the central portion, are cut away leaving a transfer notch or gap 33 in the walls which extends for 36 degrees. These gaps are sufficiently deep to permit a spring-pressed catch, generally designated as E, one of which is carried by each of the rings C1, C2, C3 and C4 to pass entirely through the gap 33 and to engage one of the notches N1 in the adjoining higher unit counter ring. A spring, generally designated as F, presses upon the catch E to keep it extended.

45 If one of the inner rings is rotated a complete revolution, the second ring will be rotated 36 degrees or one-tenth of the circumference by the catch E engaging a notch N1 of the adjoining inner ring. The catch E will be retracted by the dividing wall at the end of the movement through the gap 33. The walls defining the ends of the gap are cut to form a beveled surface at 50 each end to depress the spring easily. The spring and catch is the mechanism by which a transfer is effected between any two adjoining rings, and the transfer will take place in the direction that the ring is rotated. This means that one ring is to be rotated in one direction a full revolution to move the adjoining ring one tenth revolution.

55 The spring pressed catch E is carried by each of the counter rings C, except the innermost 10,000 unit ring C5, since this is the highest figure handled by the calculator, and no transfer is made beyond this figure.

60 A pocket 32 is formed in the inner curved wall of each

of the rings C1, C2, C3, C4 to receive the spring, generally designated as F, and its transfer pawl catch. The spring F itself has a bent central portion 34 with an arcuate end 36. When this spring is confined by the inner curved body wall defining the pocket 32, it presses the catch E against the wall so that the ring moves smoothly into the position to which it has been moved by a stylus, generally designated as S. A screw 37 secures the catch E and its hook E1 to the ring.

A plurality of circular concentric slots 40, 41, 42, 43, 10 and 44 are formed in the inside surface of the bottom piece B and each slot receives one of the extensions 11 on each of the rings. Through the concentric circular slots 40, 41, etc., is a radial slot 46 for the reception of the stylus, S. It is to be noted that the top and bottom case portions A1 and B are pivoted together by a pivot holding member 48 so that in one case portion A1 rotates with respect to the other B. Hence, when the stylus lies in the radial slot 46 rotation of the rings C in one direction brings the extension 11 to rest against the 20 stylus.

Upon the periphery of the upper case portion A1 are a series of equally spaced digits 0, 1, 2, 3, 4, 5, 6, 7, 8, and 9, designated as 53 which are read counterclockwise—the 0 is located above the totalizing figures on the slide D and the 9 appears below the totalizing figure. Before the digits 3-4 is a “+reset” notation with its notch 50 and between the 4-5 digit is a “—reset” notation with its notch 52. The notches 50, 52, are adapted to receive the head S2 of the stylus. The function of the “+reset” 30 and the “—reset” is to have the zero appear in the windows for addition and for subtraction. This is achieved in the following manner:

The pointer S1 of the stylus S is inserted into the radial recess 46 as far as it will go; the casing portion A1 and B for addition are rotated at least one revolution so that all of the projections 11 on all of the rings move—until the head 52 of the stylus fits into the +reset notch 50. The bottom casing portion B is moved counterclockwise by one hand while the top casing portion A1 is held stationary by the other hand. When the projections 11 are in their correct position all zeros should appear in the windows.

To subtract, the reverse movement of the casings A1 and B occurs as contrasted to the movements for addition—so that all digits 9 appear in the windows until the slider D is moved to the subtraction side when all zeros appear.

A radial indicator, generally designated as G, indicates the units, tens, hundreds and has openings in line with the concentric slots A4, A5, etc.

Operation.

To use the calculator for addition, the unit rings are rotated until their zero numerals appear in the sight window. This is brought about by inserting point S1 of the stylus S in the radial slot 46 and rotating the bottom case portion with respect to the upper case portion so that the rings pass one revolution and then placing the head of the stylus in the reset (+) notch 50, and moving the slide D until the A (addition) appears. All of the digits appear in the window A2 as 0. What has occurred is that all of the extensions 11 are aligned. Assuming that the number 3254 is to be calculated, the first digit 4 is placed on totalizer of the calculator by placing the point S1 of the stylus S into the notch N on the digit of the unit ring C1 at the 4 (designated 53), and moving the stylus in a clockwise direction until it is arrested by the solid portion whereupon the numeral 4 appears through the sight window A2 over the unit ring. The second digit 5 of the number is registered by placing the stylus in the tens hole of the indicator G and moving it to the notch in the ring C2 which is in radial alignment with the number 5 on the peripheral surface of the casing and by moving the stylus clockwise until it is arrested by the solid portion of the end of the slot. Similarly, the remaining digits are registered, using the indicator G and the other counter rings. In order to add a number, for example 2657 to 3254, the same series of steps are repeated, and the digits may be added in any order provided that they are placed on the proper unit ring. The total of 2657 plus 3254 will appear in the window as 5911.

When the digit 7 is added to the digit 3, the unit counter ring C1 will have revolved one complete revolu-

tion, and the tens ring C2 will advance one notch automatically, the transfer being effected by the hook E1 of the catch mechanism E previously described, engaging the keeper notch N1 only in the space 33. The walls 5 26 cause the hook E1 to be disengaged from the keeper notch N1 of the adjoining ring.

Subtraction

To perform subtraction, the totalizer is cleared, the S appears in the window and the unit cleared to have all of the digits zeros appear otherwise digits 9 will appear. The minuend is located in the totalizer by using the red numerals 54 instead of the black numbers 53 and moving the stylus S counterclockwise. A series of red digits 54 are located alongside of the black digits 53 so that the red digits 54 and the black digits total 9; that is to say the black digits 53 are read in a counterclockwise direction while the red digits are read in a clockwise direction, so that black 1 is beside red 8, black 2 is beside red 7, black 3 is beside red 6, until black 9 is alongside of red 0.

In performing subtraction, the same procedure is followed except that the minuend numerals are located on the proper unit rings by referring to the inner ring. Each counter ring C forming the minuend numeral is turned counter-clockwise by means of the stylus until the entire minuend has been set up. The subtrahend is then located as in a row of figures for addition and the counter rings are turned in a clockwise manner to complete the subtraction.

In construction, the calculator is especially adapted to be made of molded plastic composition, with spring steel inserts. The calculator is flat, light and sturdy, is simple to use, and inexpensive to manufacture, and accurate.

The calculator may be carried by the housewife to total the money she expends and can be particularly useful in super markets for shopping purposes.

All of the numerals on rings C1 and C2 may be red and all of the numerals on the other rings C3, C4, and C5 may be in black to indicate dollars (black) and cents (red). This expedites reading of the calculator.

Although my invention has been described in considerable detail, such description is intended as being illustrative rather than limiting, since the invention may be variously embodied, and the scope of the invention is to be determined as claimed.

I claim as my invention:

1. A pocket calculator comprising a flat base member having a peripheral flange thereon, a series of concentrically spaced annular grooves in said base, a top member having a flange adapted to telescope within said base member, a series of concentric annular openings in said top member, a series of rings having numerals thereon and located between said top member and said base member, a plurality of notches in said rings, each of said notches having a vertical portion which coincides with one of said annular openings in said top member, and a horizontal portion which lies on the under surface of said ring, the vertical portions of each of said notches being adapted to receive an instrument for turning its respective ring, said horizontal portions being adapted to receive a spring-pressed catch mounted on an adjacent ring, and each of said rings being further provided with a depending lug which is adapted to enter one of said concentrically spaced annular grooves in said base, and said depending lug being adapted to be engaged by a stylus whereby rotation of the base and the rings brings the rings to a zero position.

2. A calculator, comprising a disc-like body member having concentric circular dividing walls formed thereon, a plurality of numeral bearing rings adapted to be rotated between said walls, a set of notches for receiving an actuating stylus formed in said rings adjacent said numerals, a set of tens carrying notches equally spaced in each of said rings, each of said circular dividing walls being cut away for a portion of their length to form gaps therein, a pocket formed in each of said rings, a catch located in each of said pockets, said catch comprising a lever pivoted at one end and having a substantially V-shaped lug adjacent said other end, a spring located in said pocket adjacent said lever, said spring being adapted to bias said lever toward the adjacent dividing wall, said catch being pivotally connected with respect to the ring in which it is pocketed, said catch

being adapted to be compressed by said dividing walls and being adapted to project through said gap in said dividing walls and to engage one of the ten transfer notches in an adjacent ring, and a depending lug projecting downwardly on each of said rings.

3. My invention as set forth in claim 2, wherein said gaps in said walls extend approximately 36 degrees of a circle; and wherein a sight window is incorporated in said body member; and a radial slot extending in said disc-like body member whereby a stylus placed in said slot is adapted to bring said rings to a zero position when relative motion occurs between the rings and said body member.

4. In a pocket calculator to perform addition or subtraction, a plurality of rings, each ring having ten notches equally on its curved outermost periphery, a notch in one of said rings, a spring pressed catch in said notch, said catch comprising a lever pivoted at one end and having a substantially V-shaped lug adjacent said other end, a case, means on said case to keep said spring pressed catch away from said second ring for nine-tenths of the circumference of the rings, a gap in said means for one-tenth of the circumference whereby said catch in one ring may engage a notch in the adjoining ring whereby said two rings are moved simultaneously, and a de- 25

pending lug projecting downwardly on each of said rings adapted to be engaged by a stylus located at a radially extending slot in said case to bring said rings to register at a zero position when said case and said rings are relatively moved.

5. The invention of claim 4 including a slide having windows on the top of said casing, digits upon said rings, and said digits being adapted to be visible only at said window, said slide being radially movable from one position for addition and to another position for subtraction.
